PERFORATING DEVICE

Emil Kern, Long Island City, N. Y., assignor to
Acco Products, Inc., a corporation of New YorkApplication December 14, 1936, Serial No. 115,821
Renewed December 7, 1939

3 Claims. (Cl. 164—91)

The invention relates to punches and more particularly to perforating devices adapted for perforating sheets of material to facilitate binding them with prong fasteners or by other suitable means in sheaves, files or binders.

5 An object of the invention is to provide a sturdy, efficient and relatively inexpensive perforating device embodying a number of practical improvements, and especially a device in which the principal parts thereof may be readily constructed of sheet metal.

10 Another object is to provide a perforating device of the character referred to with a novelly constructed tray to receive bits punched from sheets, having novel means to frictionally retain 15 said tray in place.

Another object is to provide novel means to facilitate insertion of a sheet or sheets into the 20 perforating device.

The foregoing and such other objects of the 25 invention as will become apparent as the description proceeds, will be more readily understood from a perusal of the following specification, reference being had to the accompanying drawings, in which:

Fig. 1 is a plan view of the perforating device, showing a portion of the gauge bar broken away.

Fig. 2 is an enlarged vertical sectional view taken on line 2—2 of Fig. 1.

30 Fig. 3 is a sectional view taken on line 3—3 of Fig. 2.

Fig. 4 is a sectional view taken on line 4—4 of Fig. 2.

35 Fig. 5 is a perspective view of one of the punch guide standards.

Fig. 6 is an inverted plan view illustrating a modified form of tray, showing a portion of the base broken away.

Fig. 7 is a perspective view of the tray shown 40 in Fig. 6.

Fig. 8 is a fragmentary plan view of the device, partially broken away, showing another form of tray.

45 Figs. 9 and 10 each are fragmentary side elevational views, partially broken away, each illustrating a modified form of guide standard.

Referring to the drawings, and particularly to the embodiment shown in Figs. 1 to 5, inclusive, 50 it indicates a base which may be made of any suitable sheet metal, such as steel, formed with downwardly turned lateral edges 12 having inwardly turned spaced apart lips 13 upon each of which preferably is secured a rubber foot 14. The front end of the base 11 may be suitably closed by,

for example, a metal strap 15 which is bent at its ends and may be secured by rivets 16 or otherwise to the adjacent end portions of the lateral edges 12. Two or more standards 17 are secured upon the base 11 preferably by rivets 18, 5 said base having a raised mounting surface 19 for each standard whereby the rivet heads are elevated above the bottom face of the base.

The standards 17 are constructed of any suitable sheet metal, preferably steel, and, upon particular reference to Fig. 5, it will be noted that the sheet metal is bent to generally rectangular form, providing bottom and top walls 19 and 21, respectively, and sides 22 having upwardly projecting parallel ears 23. The bottom wall 19 and top wall 21 have vertical aligned openings 24 and 25, respectively, to receive and guide a punch 26. To assure proper alignment of one punch in each standard and to prevent escape of the lower end thereof from the associated opening in the respective bottom wall 19, an upwardly projecting boss 27 is formed from the body of the metal on each bottom wall 19. Obviously the two aligned openings in each standard afford a rigid guide permitting vertical movement 25 only of the respective punch 26.

An operating handle or lever 28 preferably is provided with diverging arms 29, which are connected adjacent their free ends, by pins 31, one to each of the punches 26. Two springs 32, one 30 resting on the top wall 21 of each standard 17, engage the respective pins 31 and normally hold the punches 26 in their uppermost position, as best shown in Fig. 2. The arms 29 of the handle 28 also carry fulcrum pins 33 at their ends 35 which extend through slots 34 in the ears 23 of the respective standard 17. The axes of the slots 34 preferably are disposed at an angle to the horizontal plane, and the pins 33 are adapted to ride downwardly in the slots as the handle 28 40 is depressed. Accordingly, the pivotal center shifts with the movement of the handle, and true vertical movement of the punches 26 is assured without their binding in the guides.

Openings or dies 35 are provided in the base 45 11 one beneath each punch 26 for co-operating therewith when the handle 28 is depressed. Consequently, when the margin of one or more sheets of material is introduced into the space 36 beneath the punches it is perforated upon depression of the handle 28. The bits of sheet material thus removed are delivered through the die openings to a tray 31. This tray preferably is formed of sheet metal and has a perpendicular flange 38 at one end and an inclined flange 39 55

at the opposite end. The bottom 40 of the tray 37 has its margins fitted into opposed grooves 41, one formed on the inside face of each lateral base edge 12. Obviously the tray may be moved in 5 and out to receive and deliver punched out bits of the sheet material. The upturned flange 38 preferably is sufficiently high to cause it to have a slight binding engagement with the under face of the base 11 when the tray is in its innermost 10 position. A cut out 42 on the edge of the base enables the user to engage the edge of the flange 38 to release the tray by pressing downwardly and pulling it outwardly when desired.

The flange 38 preferably is disposed at an incline 15 so that the bits of sheet material are caused to slide rearwardly as they are delivered to the tray. The inclination of this flange obviates a difficulty heretofore experienced in which the bits of sheet material pile up under the punches 20 and tend to jam the device instead of spreading through the tray. With the angularly disposed flange, the bits of sheet material slide rearwardly into the tray and are distributed as they accumulate.

25 To facilitate the handling of sheet material and the spacing of the perforations therein, an indicator 43 is provided on the surface of the base 11 midway between the standards 17. There is also a depression 44, slotted at each end, in the 30 body of the base 11 forward of the standards 17 to afford a support for a gauge bar 45 which is inserted through slots in the lateral edges of the base and which preferably is slit at 46 to afford a friction engagement. A projection 47 at the 35 end of the gauge bar provides a limit for the edge of the sheet material. Obviously, the gauge bar 45 may be shifted in the base and set at any desired position, so that consecutive sheets of material may be punched with the perforations spaced the same distance from the edge.

40 In the embodiment shown in Figs. 6 and 7 the inclined flange 39^a on the tray 37^a has a split lip or tang 48 extending substantially horizontal beyond its free upper edge for yieldable frictional 45 engagement in an opening 49 provided in the gauge bar depression 44. This arrangement tends to frictionally retain the tray in place. In other respects the perforating device is constructed like that form previously described and 50 like reference numerals indicate corresponding parts.

The tray 37^b, shown in Fig. 8, has one or more slits 50 adjacent each edge to provide yieldable 55 portions 51 which frictionally bear against the wall of the respective grooves 41 when the tray is in position to receive bits of sheet material. In all other respects this embodiment also is like the form shown in Figs. 1 to 5 and like reference numerals indicate corresponding parts.

60 The structure illustrated in Fig. 9 is substantially like the device first described and like reference numerals indicate like parts. In this embodiment a hole 52, of larger diameter than the fulcrum pin 33, is provided in each ear 23 instead 65 of the inclined slot previously disclosed. The tray 37^c differs from the trays previously described in that it preferably has a depression 53 in its bottom 40^c to permit finger engagement for withdrawing the tray from the base. The 70 forward edge of the bottom wall 19 of each stand-

ard 17^a preferably is extended beyond the forward edge of the standard side walls and is inclined upwardly as shown to provide a lip 54 to facilitate insertion of sheet material into the space 36. Each standard 17^a preferably is formed with a portion of its bottom wall offset downwardly and apertured to receive tangs 55 struck up from the base. The tangs are clinched over the bottom wall, as shown, to rigidly hold the standard in place.

5 The illustration of Fig. 10 differs from the previously described forms in that the forward edges of the side walls 22 of each standard 17^b is flush with the forward edge of the upwardly inclined lip 54.

10 The improved perforating devices, with the exception of the punches, springs and necessary pins and feet, are made from sheet metal stamped or otherwise formed in the desired shape. The required operations, as well as the 20 material used, are relatively inexpensive, and the devices can be manufactured at a much lower cost than has been possible heretofore. The structures, being particularly sturdy, will withstand rough and continued usage over long 25 periods.

15 Although exemplary forms of the perforating device have been illustrated and described in detail it is obvious that various changes may be made in the details of construction and arrangement of the parts shown without departing from the spirit of the invention or the scope of the appended claims.

20 I claim:

25 1. A device for perforating sheets of material comprising, a base having die openings therein, standards thereon each of sheet metal bent to provide spaced apart ears, a top and a bottom wall on each standard having guide openings in alignment with said die openings, a fulcrum pin 40 journaled in each standard, punches supported in the guide openings, and an operating lever operatively connected to the punches and fulcrumed on said pins operable to carry the punches downward to perforate a sheet of material resting over said die openings, and means on each standard to facilitate insertion of the sheet of material beneath said standards and over said die openings.

30 2. In a perforating device, a tray formed of sheet metal comprising a substantially flat body portion having its marginal end portions folded to provide flanges, one of said flanges extending upwardly substantially at right angles to the body portion and the other flange being inclined 55 upwardly and outwardly, said inclined flange terminating short of the side edges of said body portion, and finger engaging means in the bottom of said tray.

3. A perforating device comprising, a base, 60 standards each of sheet metal bent to provide a top and a bottom with guide openings therein, tangs struck from said base to engage in the bottom of each standard to secure them to the base, a pair of ears extending upwardly from each of said standards, a fulcrum pin journaled in each pair of ears, punches supported in the guide openings, and an operating lever connected to the punches and fulcrumed on said pins.
